UNITED STATES PATENT OFFICE.

EDWIN A. JOHNSTON, OF JOHNSTOWN, PENNSYLVANIA.

CLOSET-VENTILATOR.

1,342,716.

Specification of Letters Patent.

Patented June 8, 1920.

Application filed December 10, 1917. Serial No. 206,412.

To all whom it may concern:

Be it known that I, EDWIN ARTHUR JOHNSTON, a citizen of the United States, and a resident of Johnstown, in the county 5 of Cambria, and State of Pennsylvania, have invented a new and useful Improvement in Closet-Ventilators, of which the following is a specification.

My invention relates to improvements in 10 sanitary appliances, being more particularly an improvement in closet ventilators, and it consists in the constructions, combinations, and arrangements herein described and claimed.

15 An object of my invention is to provide a motor driven exhaust fan for exhausting the air from the bowl, and including a float and seat operated switch for controlling the action of the motor of the exhaust fan.

20 Another object of the invention is to provide a device as described, including a switch having a spring pressed plunger adapted to engage an arm on the seat to hold the seat in a normally slightly elevated 25 position.

Another object of the invention is to provide a device as described, including the switch having connection with the float lever, for throwing the switch and stopping 30 the motor upon flushing the bowl.

Other objects and advantages will appear in the following specification, reference being had to the accompanying drawing, in 35 which:

Figure 1 is a vertical section of a flush tank illustrating the application of the invention.

Fig. 2 is a cross section on the line 2—2 of 40 Fig. 1;

Fig. 3 is an elevation of the switch with the cover plate removed, and

Fig. 4 is a detail cross section on the line 4—4 of Fig. 3.

45 My invention consists primarily of an exhaust fan 1 operated by a motor 2 and located in a fan casing 3. The fan casing 3 communicates at one side with an air discharge pipe 4. The bottom of the casing 3 50 communicates with an exhaust pipe 5 including a hood 6 which is fitted over the over-flow pipe 7 and is spaced therefrom as at 8.

The over-flow pipe 7 leads to the bowl 90. 55 The function of the exhaust fan 1 when the motor 2 is operated, is to create a draft in

the over-flow pipe 7 exhausting the air therefrom and discharging the same into the air discharge pipe 4.

A switch mechanism 9 controls the operation of the motor. The switch mechanism 9 consists essentially of a plunger 10 having a collar 11 pressed against the bottom of the switch casing 12 by a coil spring 13 which surrounds a portion of the plunger. The 60 upper portion of the spring bears against a bracket 14 so that the plunger is always normally forced downwardly.

An arm 15 having an adjusting screw 16, is adapted to be pressed downwardly 70 through the engagement of the plunger 10, with the adjusting screw 16. The seat 17 is normally held slightly elevated through the action of the spring 13. The arm 15 is pivoted at 18 to the hinge 19 screwed to the 75 bottom of the seat at 20. The arm 15 has a shoulder 21 which abuts the shoulder 22 formed on the hinge 19 below the pivot 18.

A solid connection is substantially afforded by the arrangement of the shoulders on the arm and hinge respectively, so that when the spring 13 presses the plunger 10 downwardly, and the plunger is in engagement with the adjusting screw 16, the arm 15 thus being pressed downwardly, slightly rocks the seat 17 on the pivot 18 whereupon the front end thereof is slightly elevated. 80

Upon applying a weight to the seat, the arm 15 is moved upwardly, and the plunger 10 shifts a switch arm 23 inside of the switch casing 12, into engagement with a pair of contacts 24 in circuit with the motor 2. The circuit through the motor is then closed and the motor operates to rotate the 85 exhaust fan 1. The switch arm 23 has a V-shaped projection 25 which engages a recess 26 in the end of the plunger 10. A spring 27 pulls the switch arm 23 down, and the projection 25 into firm engagement with 90 the recess in the plunger. 100

A latch 28 has a heel 29 which catches the end of the switch arm 23 to hold it in the terminal engaging position just referred to. The latch 28 is in the shape of a bell crank 105 including the arm 30 and the pivot lugs 31. A spring 32 holds the latch in the position shown in Fig. 3 wherein the member 28 is seen to engage the point of the switch arm 23 adjacent to the beveled end 23^a. The 110 purpose of the beveled end 23 is to engage the heel 29 which is slightly rounded on the

under side to facilitate the movement, and displace the latch so that the switch arm may assume the terminal engaging position and be held in this position by the heel 29 5 which springs back under the end of the switch arm.

The motor is stopped when the tank is flushed, through the action of the float 33 including the float lever 34, on a switch 10 hook 35. The switch hook 35 includes a cable 36 which is attached at one end to the switch hook, and at the other end to a link 37 in the switch casing 12. The link 37 is in turn connected to the arm 30 of the latch 15 28. The cable 36 runs through a tube 38 which is curved at the upper end to properly guide the cable over into the flushed box where it is connected to the hook 35. When the tank is flushed as above stated, 20 the float 33 moves downwardly with the receding water level until the float lever 34 engages the bend of the hook 35, when the cable 36 and consequently the link 37, is pulled upwardly, rocking the latch 28 on 25 the pivot 31, releasing the end of the switch arm 23 which is then pulled down by the spring 27, breaking the motor circuit.

These are the essential features of the invention and the particular type of tank 30 mechanism and the manner in which it is applied is of little consequence. However, Fig. 1 illustrates a typical tank mechanism which may be briefly described. The float lever 34 is connected to a valve stem 39 and operates the water inlet valve 40. An after-fill pipe 41 connects to the valve 40 and has a goose neck 42 which discharges into the over-flow pipe 7.

This arrangement introduces a novel 40 structural feature in that the over-flow pipe 7 and the exhaust pipe 5 which is practically a continuation thereof, is made to perform the combined functions of conducting the water to the bowl 90 and providing a passage for the exhausted air. At the same 45 time the hood 8 offers a convenient channel which accommodates the straight portion of the goose neck. The passage of the exhausting air in the pipe 7 and the continuation 50 5, is not broken by reason of the separated pipes, since a water seal is formed in the hood 8 beneath the end of the pipe 7.

The operation of the device is as follows: 55 The motor 2 and fan 1 are normally idle and the switch arm 23 is in normal disconnection with the terminals 24. The spring 13 normally presses the plunger 10 downwardly, consequently slightly raising the seat 17.

60 A weight being applied to the seat, rocks the seat and the arm 15 on the mutual fulcrum 18, pressing the plunger 10 upwardly against the tension of the spring 13, and moving the switch arm 23 between the terminals 24. The latch 28 locks the switch

arm in this position in the manner previously described. The motor circuit is thus closed and the fan 1 operates to create the current of air in the pipes 7, 5 and 4.

Upon operation of the flushing mechanism, the float 33 lowers until the float lever 34 engages the bend in the switch hook 35. The switch hook is thus carried down, and a pull is exerted on the cable 36, raising the link 37 and rocking the latch 28. The heel 75 29 being thus freed from the end of the switch arm 23, permits the stored tension in the spring 27 to pull the switch arm 23 away from the terminals 24 to break the motor circuit and stop the rotation of the fan. 80

It will be understood that ordinarily few people continue to occupy the seat after flushing, and so the weight is relieved from the plunger 10, permitting the arm 23 to fall upon being released by the latch 28. 85

It has been explained that a pressure upon the seat 17 causes the motor to operate. The fact that the motor is operating, serves as an indication that the tank must be flushed before the function of the switch mechanism 90 9 may come into play to stop the operation of the motor. As incidental details of construction, the switch hook 35 is preferably made of rigid material and is connected to the cable 36 which is flexible. Obviously 95 the cable and hook may be made continuous if it be found desirable to do so. Again, the screw 16 is made adjustable so that the seat 17 may be raised to various heights through the action of the spring 13. It will 100 be understood that the seat 17 may readily be raised without disturbing the switch mechanism 9 in the least. But as soon as the shoulders 21 and 22 come into contact, the connection of the arm 15 with the hinge 105 19 is, for all purposes, rigid.

It will be understood that the switch shown is merely for purposes of illustration, as any suitable commercial or other form of switch could be used without departing from 110 the form of my invention. Instead of leading the wires to a pair of terminals as illustrated in Figs. 3 and 4, the wires may be led to the pivotal point of the switch arm 23 and to a single terminal 24, respectively. The advantage of this arrangement is, that arcing is less liable to occur, but as stated above, the arrangement of the switch and the parent connections, may be varied to suit the particular requirements. 115

While the construction and arrangement of the device as illustrated in the accompanying drawing is that of a generally preferred form, obviously modifications and changes may be made without departing 125 from the spirit of the invention or the scope of the claims.

I claim:

1. In a closet ventilator, an over-flow pipe, an exhaust pipe having a hood covering the 130

end of the over-flow pipe and adapted to form a water seal therebetween, a motor operated fan in the exhaust pipe, seat-operated means for energizing the motor, and 5 float-operated means coacting with said seat-operated means for deenergizing the motor.

2. In a closet ventilator, a pivoted switch arm, motor circuit terminals engageable by 10 said arm, an insulating plunger in engagement with the switch arm, a seat-operated arm arranged to shift the switch arm through the plunger, and means pressing the plunger into engagement with the seat-operated arm.

15 3. In a closet ventilator, a pivoted switch arm, motor circuit terminals engageable by said arm, an insulating plunger in engagement with the switch arm, a seat-operated arm arranged to shift the switch arm 20 through the plunger, means pressing the plunger into engagement with the seat-operated arm, and means associated with said terminals, for holding the switch arm in the circuit closing position.

25 4. In a closet ventilator, a combined water over-flow and air exhausting pipe, a motor driven fan for exhausting air in the pipe, a pivoted switch arm, motor circuit terminals engageable by said arm, a plunger in engagement with the switch arm, a seat-operated arm engaging the plunger and 30 adapted to shift the switch arm, means pressing the plunger into engagement with the seat-operated arm, means associated with said terminals, for holding the switch arm in the circuit closing position, and float-operated means including a switch hook and 35 cable in connection with said terminal associated means, for releasing the switch arm.

40 5. In a device as described, the combination of the switch mechanism and seat, an arm carried by the seat, a plunger included in the switch mechanism and engaging the arm, a spring pressing the plunger into such 45 engagement, and a switch arm in engagement with the plunger and movable through the shifting of the seat.

50 6. In a device as described, the combination of the switch mechanism and seat, a shoul- 55 dered hinge secured to the seat, a shoul- dered arm in pivotal relationship to the hinge, the abutment of the shoulders forming a rigid connection, a plunger included in the switch mechanism and engaging said arm, and a spring acting on the plunger to hold the seat at a normally slight elevation through the rigid connection of the arm and hinge.

7. In a device as described, the combina-

tion of the switch mechanism and seat, a 60 shoul-dered hinge secured to the seat, a shoul-dered arm in pivotal relationship to the hinge, the abutment of the shoulders forming a rigid connection, a plunger included in the switch mechanism and engag- 65 ing said arm, a spring acting on the plunger to hold the seat at a normally slight elevation through the rigid connection of the arm and hinge, and an adjustable screw located at the point of engagement of the 70 plunger with said arm.

8. In a device as described, the combination of the seat carried arm, a switch mechanism carried plunger contacting said arm, a spring holding the plunger in contact, circuit terminals, a switch arm having a projecting portion engaging the plunger and 75 adapted to be moved into contact with the terminals upon movement of said arm, and a locking latch including a heel for engag- 80 ing the end of the switch arm to hold it in engagement with the circuit terminals.

9. In a device as described, the combination of the seat carried arm, a switch mechanism carried plunger contacting said arm, 85 a spring holding the plunger in contact, circuit terminals, a switch arm having a projecting portion engaging the plunger and adapted to be moved into contact with the terminals upon movement of said arm, 90 a locking latch including a heel for engag- 95 ing the end of the switch arm to hold it in engagement with the circuit terminals, and a float-operated connection to said latch for moving the latch to release the switch arm, including a float lever engageable switch hook and a flexible cable.

10. In a device as described, the combination of the switch mechanism including the switch arm latch, a link connected to the 100 latch, the float lever, a rigid switch hook including a loop-head portion receiving the float lever and adapted to be engaged thereby during a portion of the downward movement of the float lever, a cable connected to 105 said hook and the link, and a tube including a curved portion for guiding the cable.

11. In a closet ventilator, an exhaust pipe in communication with the bowl, means for exhausting the air from the pipe, seat-con- 110 trolled means arranged to render said ex- hausting means operative upon application of pressure to the seat, and means operative by a movable portion in the flush tank ar- ranged to render the exhausting means in- 115 operative upon flushing the bowl.

EDWIN A. JOHNSTON.
